EXPANDABLE GEM SETTING

Walter H. Glaser, Kaufbeuren-Neugablonz, Germany, assignor to E. H. Ashley & Company, Inc., Providence, R.I.

Filed July 6, 1971, Ser. No. 160,249

Term of patent 14 years

Int. Cl. D11—01

U.S. Cl. D45—1 B

FIG. 1

FIG. 2

FIG. 3

FIG. 4

FIG. 5

FIG. 6

FIG. 1 is a front elevational view of an expandable gem setting showing my new design as it would appear in expanded position on a gem of oval configuration;

FIG. 2 is a side elevational view thereof;

FIG. 3 is a rear elevational view thereof;

FIG. 4 is a bottom plan view thereof;

FIG. 5 is a top plan view thereof; and

FIG. 6 is a front elevational view thereof as it would appear in its normal and unexpanded position.

I claim:

The ornamental design for an expandable gem setting, substantially as shown and described.
